THROTTLE CONTROL

John L. Griggs, Wichita Falls, Tex.

Application January 13, 1941, Serial No. 374,285

12 Claims. (Cl. 192—3)

This invention relates to an improvement in throttle controls for internal combustion engines and the like, of the character usually provided with a governor constructed to limit the maximum speed of the engine.

Heretofore, internal combustion engines have been controlled by throttle mechanism capable of being set to maintain a constant operating speed for the engine, and in other instances, governors have been provided for limiting the maximum speed of operation thereof. In either instance, it is desirable frequently to provide for manual control over the speed of the engine that may be made instantly available when desired.

The object of this invention is to provide for the operation of the engine at a manually controlled set speed that may be released however instantaneously for manual control of the engine by the operator either to reduce or increase the speed of operation of the engine.

This object is accomplished by synchronizing the manual and governor controls of the engine with provision by which the engine may be operated at a set speed that may be released instantaneously, restoring the control to manual operation.

A preferred embodiment of the invention is illustrated in the accompanying drawings, in which:

Fig. 1 is a fragmentary side elevation of a portion of an internal combustion engine, showing the invention applied thereto, with a part in section;

Fig. 2 is an enlarged side elevation of the control rod and lever assembly detached;

Fig. 3 is a side elevation of an automatic governor modified in accordance with this invention, with the cover plate removed;

Fig. 4 is an enlarged side elevation of the control mechanism from one side;

Fig. 5 is a similar view from the opposite side thereof;

Fig. 6 is a vertical cross section therethrough on the line 6—6 of Fig. 4;

Fig. 7 is a diagrammatic view of the control tracks in one condition; and

Fig. 8 is a similar view showing another cycle of control operation.

The invention is shown as applied to an internal combustion engine of the character usually employed in a motor vehicle, in which the engine is designated generally by the numeral 1 and is supplied with fuel through an intake manifold 2 from a carburetor 3.

The supply of fuel to the engine is regulated by the usual throttle valve 4 secured to an arm 5, the free end of which is connected by a link 6 with a lever 7. Said lever is pivotally mounted at 8 on the floor boards 9 of the motor vehicle in the usual way. A foot pedal or accelerator 10 is attached to the lever 7 and extends through the floor boards 9 to a position within convenient reach of the operator, for moving the lever 7 in one direction against the tension of a spring 11.

The intake manifold 2 is shown as provided also with a governor of conventional structure, designated generally by the numeral 12, by means of which the maximum operating speed of the engine may be limited, which is done usually in the type of governor illustrated by the adjustment of a control arm 13 (Fig. 3) by means of a leaf spring 14 on the free end of which the arm 13 bears. Adjusting means for the leaf spring is shown at 15. The construction and manner of operation of this governor being well understood in the art, need not be illustrated in detail. Normally, the governor acts to limit the maximum operating speed of the engine according to the set position of the adjusting means 15 tilting the spring in one direction or the other to vary the position of the arm 13. The spring 14 is shown in Fig. 3, substantially in the position where the governor control is open for maximum operating speed of the engine, and the spring 14 may be swung downward in Fig. 3 to any desired set position for limiting the speed of operation of the engine.

Provision is made in this invention for manually shifting the governor spring 14 from a lowered position, reducing the speed of operation of the engine, to an open position for maximum speed of operation of the engine in response to the operation of the throttle control. This is accomplished by a lockout arm 16 in position to engage and force upward the free end of the governor spring 14 when said arm 16 is moved from the full line to the dotted line position in Fig. 3. The arm 16 is supported on a shaft 17 journaled in the housing of the governor 12, and carrying an arm 18 on the outer end thereof. This arm 18 has an opening 19 therein slidably receiving one end of a rod 20, the opposite end of which rod 20 is pivotally connected with a sleeve bracket 21 slidably receiving the throttle rod 6. A spring 22 is sleeved over the free end of the rod 20 and is interposed between a stop 23 thereon and the adjacent side of the arm 18 to provide a resilient abutment for the movement of said arm 18 upon sliding movement of

the rod 20 in one direction. The arm 18 is moved in the opposite direction by a spring 24 connected therewith, as shown in Fig. 1. The lost-motion connection is provided between the rods 6 and 20 by the sleeve bracket 21 which permits limited sliding movement of the rod 6 relative thereto under control of a set collar 25 adjustably mounted on the rod 6 to limit the extent of movement of the rod before said collar engages the sleeve bracket 21 and moves the rod 20.

For holding the throttle in a set position, I have provided control mechanism in the form of a supporting plate 26 mounted in a fixed position relative to the engine 1, as on a support 27 forming a part of the motor vehicle frame structure. The supporting plate 26 is elongated as shown in Figs. 4 and 5 and has longitudinally extending guideways 28 therein slidably receiving a block 29. The block 29 is adapted to be moved lengthwise of the guideways 28 by the lever 7, the lower end portion of which is bifurcated at 30 and receives in the bifurcation thereof a pin 31 attached to the block 29, whereby swinging movement of the lever 7 causes longitudinal sliding movement of the block 29.

A guide arm 32 is pivotally supported at 33 on the block 29 and carries a pin 34 on the free end thereof which pin 34 is in position to ride upon a track 35 rigidly fixed to the inner side of the supporting plate 26 at one side of the block 29, as shown in Fig. 6. The pin 34 is held in a riding position on the track 35 by a spring 36 connected with the guide arm 32. The track 35 has a main inclined portion designated 35a in Figs. 7 and 8, from the outer end of which depends an oppositely inclined portion 35b terminating in an outer end portion 35c adapted to receive and guide the pin 34, as hereinafter described. Spaced above the portion 35c of the track is a guide stop 37 arranged substantially in longitudinal alignment with the inclined portion 35a of the track, but spaced therefrom, and supported upon the inner side of the supporting plate 26.

Interposed between the track portion 35a and the guide stop 37 is a switch arm 38 constructed with a pointed end arranged substantially at the juncture between the track portions 35a and 35b, and with an upper surface inclined therefrom terminating in an end lip 39 overlapping the lower end of the guide stop 37, and spaced therefrom a distance at least as great as the diameter of the guide pin 34 for passage of said pin therebetween and between the end of the guide stop 37 and the switch arm 38. Said switch arm 38 is supported on a shaft 40, journaled in the supporting plate 26 and having a bell crank lever 41 fixed on the outer end thereof. One end of the bell crank lever 41 has a spring 42 connected therewith, while the opposite end thereof underlies one arm of a bell crank lever 43 pivoted at 44 to a side of the supporting plate 26, while the other arm of said bell crank lever 43 is pivotally attached to a connecting rod 45, extending therefrom to the brake actuating mechanism of the vehicle. The connection is such that the application of the brakes to set positions will move the connecting rod 45 in the direction indicated by the arrows in Figs. 1 and 4, tripping the bell crank lever 41 and swinging the switch arm 38 from the position shown in Figs. 5 and 7 to the position shown in Fig. 8. This will allow the guide pin 34 to move backward from a position at one end of the switch arm 38 directly to

the track portion 35a. In this position, the guide pin 34 is retained in a pocket 46 between the end of the switch arm 38 and the guide stop 37 directly over an elongated abutment 47 fixed to the inner side of the supporting plate 26.

In the operation of this control, the governor 12 is set initially by the adjusting means 15 for a predetermined maximum speed of operation of the engine, and the collar 25 is adjusted also on the link 6, so as to provide for sufficient movement of the arm 5 to open the throttle valve 4 to an extent slightly in excess of the maximum volume of opening of the throttle valve provided in the governor 12. This will permit the manual acceleration of the engine up to the governor speed, thus allowing the governor to function without interference by the manual control.

In the operation of the accelerator pedal 10 to open the throttle valve 4, the movement of the lever 7 causes corresponding swinging movement of the bifurcated portion 30 thereof, and through the pin 31 slides the block 29 along the guideways 28 to move the guide arm 32 lengthwise of the supporting plate 26. During this movement, the guide pin 34 rides initially on the track portion 35a, as indicated in Fig. 7. The continued movement of the lever 7 by the accelerator pedal causes the guide arm 32 to move the guide pin 34 beyond the upper end of the track portion 35a, where it will ride over the upper surface of the switch arm 38 and pass over the end lip 39, dropping onto the guide stop 37 under the influence of the spring 36, thence into the pocket 46 due to the presence of the lug 47. This locks the accelerator and throttle in advanced open position, maintaining this condition without the necessity for the operator to hold his foot on the accelerator pedal 10.

However, if the operator desires an increased speed of operation of the engine, it is necessary merely to depress the foot pedal 10 further, which moves the guide pin 34 out of the pocket 46, as indicated by the arrows in Fig. 7, where it drops onto the track portion 35c and continues thereon to the extent necessary according to the depression of the foot pedal. Then when the foot pedal is released, the pin 34 follows back along the track portions 35c, 35b and under the point of the switch arm 38, onto the track portion 35a to its initial position.

In the event that it becomes necessary to apply the brakes instantaneously, when the guide pin 34 is held in the pocket 46, without sufficient time first to release the guide pin from said pocket by further depression of the accelerator pedal 10, provision is made for opening the pocket 46 automatically, as indicated in Fig. 8. This is accomplished by the connection 45 to the brake rigging or brake operator, through which the movement thereof in applying the brakes swings the bell crank lever 43 to trip the bell crank lever 41 (Fig. 4), and thus rotate the shaft 40, carrying the switch arm 38, in the direction indicated by the arrow in Fig. 8, which allows the guide pin 34 to move from the pocket 46 directly along the upper surface of the lug 47 to the upper end of the track portion 35a, thence to its initial position as indicated by the arrows in Fig. 8.

The adjustable collar 25 is set on the link 6 in such position that the operator may, at will, advance the accelerator to such an extent as to lock out the governor 12 by extended movement of the link 6 until the collar 25 engages the sleeve bracket 21 and moves the latter forward there-

with, pushing the rod 20, and through the spring 22, the arm 18, to move the lockout arm 16 upward to the dotted line position in Fig. 3, where it engages the spring 14 and moves it upward to its highest position thereby opening to the fullest extent the throttle of the governor 12 and providing for increased acceleration of the engine under the control of the throttle 4. Then when the accelerator pedal 10 is released, the spring 24 returns the arm 18 to its initial position releasing the governor 12 and allowing it to remain in its operative position to control the maximum operating speed of the engine.

This throttle control is particularly desirable for motor vehicles where the drivers desire to travel at a constant predetermined speed, and at the same time find it necessary to have the control mechanism sufficiently flexible to provide for increased speed if the demand arises or to decrease the speed instantaneously in an emergency.

I claim:

1. In throttle control mechanism, the combination of a main throttle, an accelerator, means for connecting the accelerator with the main throttle for operating the same, and means for automatically locking said accelerator in a predetermined advanced position by the movement of the accelerator to said advanced position, said locking means being constructed to release the accelerator upon further advancing movement thereof in said same direction of movement past said advanced position.

2. In throttle control mechanism, the combination of a main throttle, an accelerator, means operatively connecting the accelerator with the main throttle, control means for the accelerator including a movable member operatively connected with the accelerator for movement thereby, a guide member connected with the movable member, and locking means in position for engagement by the guide member to hold the movable member and the accelerator in an advanced position.

3. In throttle control mechanism, the combination of a main throttle, an accelerator, means operatively connecting the accelerator with the main throttle, control means for the accelerator including a support having guideways therein, a block slidably mounted in the guideways, a guide arm pivotally carried by the block and having a guide pin thereon, a track connected with the support in position for guiding the movement of the pin therealong, and means for locking the pin in an advanced position relative to the track.

4. In throttle control mechanism, the combination of a main throttle, an accelerator, means operatively connecting the accelerator with the main throttle, control means for the accelerator including a support having guideways therein, a block slidably mounted in the guideways, a guide arm pivotally carried by the block and having a guide pin thereon, a track connected with the support in position for guiding the movement of the pin therealong, means for locking the pin in an advanced position relative to the track, said locking means including a pocket for receiving and holding the pin and having an outlet at one side thereof for releasing the pin therefrom upon advanced movement of the accelerator, and an extended track portion in position to receive the pin after release from the pocket and to direct the same backward to the first-mentioned track.

5. In throttle control mechanism, the combination of a main throttle, an accelerator, means operatively connecting the accelerator with the main throttle, control means for the accelerator including a support having guideways therein, a block slidably mounted in the guideways, a guide arm pivotally carried by the block and having a guide pin thereon, a track connected with the support in position for guiding the movement of the pin therealong, means for locking the pin in an advanced position relative to the track, said locking means including a switch arm constructed for engaging and holding the guide pin in an advanced position of the accelerator, a shaft supporting said switch arm for swinging movement, and means for moving said switch arm to release the guide pin therefrom for return to the track.

6. In throttle control mechanism, the combination of an accelerator adapted to be connected with a throttle, and control means for the accelerator comprising a support, means mounting said support for sliding movement, a guide arm pivotally carried by the support and having a guide pin thereon, a track in position for guiding the movement of the pin therealong, and means for locking the pin in an advanced position relative to the track.

7. In throttle control mechanism having an accelerator, control means for the accelerator comprising a support, means mounting said support for sliding movement, a guide arm pivotally carried by the support and having a guide pin thereon, a track in position for guiding the movement of the pin therealong, and means for locking the pin in an advanced position relative to the track.

8. In throttle control mechanism having an accelerator, control means for the accelerator comprising a trackway, a guide mounted on the trackway, means for connecting said guide with the accelerator for actuation thereby, and means for locking the guide in an advanced position relative to the trackway, said locking means including a pocket for receiving and holding the guide.

9. In throttle control mechanism having an accelerator, control means for the accelerator comprising a trackway, a guide mounted on the trackway, means for connecting said guide with the accelerator for actuation thereby, and means for locking the guide in an advanced position relative to the trackway, said locking means including a pocket for receiving and holding the guide and having an outlet at one side thereof for releasing the guide therefrom upon advanced movement of the accelerator connecting means.

10. In throttle control mechanism having an accelerator, control means for the accelerator comprising a trackway, a guide mounted on the trackway, means for connecting said guide with the accelerator for actuation thereby, means for locking the guide in an advanced position relative to the trackway, said locking means including a pocket for receiving and holding the guide and having an outlet at one side thereof for releasing the guide therefrom upon advanced movement of the accelerator connecting means, and an extended track portion in position to receive the guide after release from the pocket and to direct the same backward to the first-mentioned trackway.

11. In throttle control mechanism having an accelerator, control means for the accelerator comprising a trackway, a guide mounted on the trackway, means for connecting said guide with the accelerator for actuation thereby, means for

locking the guide in an advanced position relative to the trackway, said locking means including a pocket for receiving and holding the guide, said pocket being constructed for opening movement, and brake-actuated means for opening said pocket to release the guide therefrom.

12. In throttle control mechanism, the combination of an accelerator adapted for connection with a throttle, means for locking said ac-

celerator in an advanced position automatically upon movement of said accelerator to said advanced position, means for automatically releasing said locking means upon further advancing movement of the accelerator in the same direction, and separate means for releasing said locking means without advancing movement of the accelerator.

JOHN L. GRIGGS.
